UNITED STATES PATENT OFFICE

LEWIS H. MORRILL, OF FORT WAYNE, INDIANA, ASSIGNOR TO INTERNATIONAL HARVESTER COMPANY, A CORPORATION OF NEW JERSEY

INTERNAL-COMBUSTION ENGINE

Application filed December 28, 1929. Serial No. 417,052.

This invention relates to an internal combustion engine, and particularly to a liquid cooled head construction therefor.

The object of the invention is to provide an improved head construction having water jacket spaces to enable circulation at high velocity over the cylinder head walls, around the intake and exhaust pipes, and around the valve guides, in a manner best adapted to transfer the heat from these parts and prevent the formation of steam pockets or bubbles.

Briefly, this object may be achieved in the provision of an integrally cast head having appropriate passages, water jacket spaces, and deflecting walls for achieving the desired results. It is to be understood that the circulation in the head is impelled by a pump from the engine and that such circulation in the head is entirely independent of and separate from the water cooling system for the engine block. As a result, it is possible to keep the water in the block at a uniform temperature, and the separate circulating system in the head is effective quickly to transfer the heat from the head, which is highly desirable in maintaining the volumetric efficiency of the engine.

In the drawings showing an illustrative embodiment of the invention by way of example,—

Figure 1 is a sectional view along horizontal planes, as viewed looking down along the section line 1—1 in Figure 3;

Figure 2 is a fragmentary view showing only one end of the head, the same being a section taken along vertical lines, as seen along the line 2—2 of Figure 3; and,

Figure 3 is a general transverse cross sectional view.

The block of the engine is shown at 10, having the usual water jacket 11 surrounding the cylinder wall 12. An inlet water manifold pipe 13 extends longitudinally along one side of the engine and is secured in any appropriate manner to the block 10, the said manifold being in communication with a number of passages 14 that lead upwardly, as best shown in Figure 3.

The improved integrally cast cover or

head for the block 10 is generally indicated at 15, the same including cylinder head walls 16 and inlet and exhaust pipes 17, said pipes in a conventional manner communicating with the cylinders through the head 16. The conduits 14 communicate with openings 18 in the bottom of the cover 15, and surrounding each of these openings 18 is a vertical wall having two angularly related extensions 19, there being a cover plate 20 fitting over the wall extensions and arranged in parallelism with the top side of the wall 16 over the cylinders or compression chamber. As best shown in Figure 1, a supplementary, vertical wall 21 is provided having angularly related wing extensions 22. Thus, it will be seen that the walls 22 and walls 19 form in effect flared nozzles for directing the cooling liquid around the inlet and exhaust pipes 17 and over the cylinder head walls 16 at increased velocity, thereby serving best to wash these surfaces, quickly to transfer the heat therefrom and to prevent the formation of steam pockets. It is to be noted that the nozzle effect is augmented, as best shown in Figure 3, by the close arrangement of the cover wall 20 with respect to the cover wall 16. This is also very well shown in Figure 2.

Valve guides are shown at 23, and, due to the inclined upper wall 24 and because the heat laden water naturally rises anyway, it passes around these valve guides 23 to keep the same cool. The wall 24 over the pipes 17 then runs in a horizontal direction and forms a bottom wall or floor 25 for an outlet manifold 26, there being, at suitably spaced intervals in said floor 25, a plurality of holes 27 which receive the water from the jacket spaces already disclosed. This water then passes out through an exhaust outlet 28 and then is led in any appropriate manner back to a radiator or some other similar heat dissipating arrangement.

From this description it will be seen that a separate, pump impelled circulating system is provided for an engine head, which is independent of and separate from the water jackets of the engine block. The holes 27 are so arranged that they uniformly distribute the water from the head into the out-

let manifold 26. The feature of casting this manifold integrally with the head insures the maintenance of a large volume of water over the exhaust ports and carries the hot water and steam away rapidly, thereby dissipating the heat from the combustion and valve port surfaces.

From this description it can now be seen that a simple and effective structure has been provided which achieves all of the desirable objects of the invention.

It is the intention to cover all such changes and modifications as do not materially depart from the spirit and scope thereof, as is indicated in the following claims.

What is claimed is:

1. A liquid cooled head for an internal combustion engine, said head comprising cylinder head walls, intake and exhaust pipes in communication therewith, valve guides, there being jacket spaces for the cooling liquid around said members, an inlet manifold for the liquid, and angularly related deflecting walls for causing the liquid to wash over the cylinder head walls and around the intake and exhaust pipes.

2. A liquid cooled head for an internal combustion engine, said head comprising cylinder head walls, intake and exhaust pipes in communication therewith, valve guides, there being jacket spaces for the cooling liquid around said members, an inlet manifold for the liquid, and walls forming nozzles for causing the liquid to wash over the cylinder head walls and around the intake and exhaust pipes at high velocity.

3. A liquid cooled head for an internal combustion engine, said head comprising cylinder head walls, intake and exhaust pipes in communication therewith, valve guides, there being jacket spaces for the cooling liquid around said members, an inlet manifold for the liquid, angularly related, vertically disposed deflecting walls, a cover for said walls, said vertical walls and cover constituting nozzles for causing the liquid to wash over the cylinder head walls and around the intake and exhaust pipes at high velocity.

4. A liquid cooled head for an internal combustion engine, said head comprising cylinder head walls, intake and exhaust pipes in communication therewith, valve guides, there being jacket spaces for the cooling liquid around said members, an inlet manifold for the liquid, angularly related vertically arranged, deflecting walls for causing the liquid to wash over the cylinder head walls and around the intake and exhaust pipes, and an outlet manifold having openings to receive the cooling liquid from said jacket spaces.

5. A liquid cooled head for an internal combustion engine, said head comprising cylinder head walls, intake and exhaust pipes in communication therewith, valve guides, there being jacket spaces for the cooling liq-

uid around said members, an inlet manifold for the liquid, walls forming nozzles for causing the liquid to wash over the cylinder head walls and around the intake and exhaust pipes at high velocity, and an outlet manifold having openings to receive the cooling liquid from said jacket spaces.

In testimony whereof I affix my signature.

LEWIS H. MORRILL.
